COMBINED ELECTRIC COOKING AND SERVING UTENSIL

Daniel E. McCue, Santa Barbara, Calif., assignor to Rival Manufacturing Company, Kansas City, Mo.

Filed Feb. 14, 1972, Ser. No. 226,368

Term of patent 14 years

Int. Cl. D7—02

U.S. Cl. D7—94

Fig. 1.

Fig. 2.

Fig. 3.

FIG. 1 is a top plan view of a combined electric cooking and serving utensil showing my new design;

FIG. 2 is a side elevational view thereof; and

FIG. 3 is an elevational view as seen from the left of FIG. 2.

The characteristic features of my design reside in the combination of a wide flat upper rim portion of the utensil which receives the inwardly tapering dome-like cover interiorly thereof; the integrally formed handles; and the supporting foot portions which have their outer surfaces in substantially the same plane as the outer surface of the lower portion of the utensil side wall.

I claim:

The ornamental design for a combined electric cooking and serving utensil, as shown and described.
